Patented Nov. 28, 1916.

UNITED STATES PATENT OFFICE.

JOEL KIMMEL, OF NEW YORK, N. Y.

BATHING-SHOE.

1,206,548.

Specification of Letters Patent. Patented Nov. 28, 1916.

Application filed August 3, 1916. Serial No. 112,922.

To all whom it may concern:

Be it known that I, JOEL KIMMEL, a subject of the Emperor of Austria-Hungary, and a resident of the city of New York, 3 borough of Manhattan, in the county and State of New York, have invented a new and Improved Bathing-Shoe, of which the following is a full, clear, and exact description.

10 This invention relates to boots and shoes and has particular reference to bathing shoes.

15 Among the objects of the invention is to improve this class of shoes with respect to comfort and durability when subjected to the sea water.

20 Another object of the invention is to improve the construction of bathing shoes adapting them to retain their shape and present a neat appearance for the longest possible time.

25 With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to 30 the accompanying drawings, in which like reference characters designate the same parts in the several views, and in which—

35 Figure 1 is a side elevation of my improved bathing shoe; Fig. 2 is a vertical longitudinal section of the same; Fig. 3 is a vertical transverse section on the line 3—3 of Fig. 2; Fig. 4 is a horizontal transverse section on the line 4—4 of Fig. 1; Figs. 5 and 6 are detail perspective views of parts 40 of the heel structure; and Fig. 7 is a plan view of the shank and parts adjacent thereto.

45 Referring now more particularly to the drawings, I show a shoe designed especially for bathing purposes, but having some characteristics adapted to be incorporated in shoes of other styles. Practically all of the parts, therefore, are made of waterproof material so as to withstand the water to 50 which such shoes are subjected. The sole 10 is made of rubberized fabric of sufficient weight or thickness for the purpose and to increase its durability and enhance its appearance, it is bound around its edge, as indicated at 11, with a waterproof binding.

At the shank portion, the sole is reinforced with a metal arch support 12 extending between the ball of the foot and the heel. This plate is secured rigidly to the upper surface of the shank portion of the sole by 50 means of rivets 13, two of which are at the front end of the plate and the other two are arranged in a longitudinal axis of the plate between its center and the heel end. The heel end of the plate is notched, as indicated 55 at 12', to facilitate the assemblage of the other parts, as will be described more in detail below. The last two mentioned rivets serve as pointers to indicate to the operator the location of the notch 12'. 73

The heel is made of waterproof material and may be of any suitable design or size or comprise any suitable number of lifts, shown, however, as comprising two lifts 14 and 15. The rear end of the sole 10 is beveled or tapered at 10' and likewise the steel or other metal arch support 12 is beveled all the way around. 75

At 16 I show a pad of a good quality of leather located at the heel and extending 80 over the rear end of the arch support and beneath the rear end of the main insole 17. This pad is preferably skived or thinned entirely around its edge and serves several important functions. First, it protects the 85 heel of the wearer from injury due to the notching of the metal plate or any other irregularities which may be occasioned in the construction of the heel portion of the shoe and, secondly, since the insole 17 and 90 the other principal parts are made of either waterproof cloth or rubber composition, the heel fastening devices, but for the pad 16, would be more likely to fail to hold properly. The lift 14 is secured by a series of 95 nails 18 or their equivalent passing upwardly through the parts above described and clenched into the insole. The lift 15 in turn is secured in place by means of longer nails 19, the center one of which at 100 the front of the heel is driven directly through the notch 12', the operator being guided for this purpose by the rearmost two of the rivets 13.

The heel structure above the heel proper 105 comprises a quarter 20 made in two parts connected in a vertical seam at the back. The lower edge of the quarter extends beneath the rear ends of the sole and insole and is secured by the heel fastening devices, 110

as shown in Figs. 2 and 3. A counter 21 or heel stiffener, as shown in Fig. 5, is employed to give comfort and permanency to the form of the heel. This counter is made 5 preferably of hard rubber or some suitable similar material of a waterproof nature and is held in place between the two parts of the quarter and a one piece waterproof reinforcement strip 22, see Fig. 6. The lower 10 end of this strip 22 is slotted longitudinally so as to provide a proper fit therefor while folding beneath the rear end of the pad 16 and insole. This slit is indicated at 23 and the slotted lower end of the strip is engaged 15 by some of the heel fastening devices. The upper end of the strip 22 is secured to the upper end of the back portion of the quarter by stitching 24.

I make the vamp 25 and upper 26 all of 20 one piece of material, preferably of a waterproof fabric of good quality and having the adaptability of retaining its shape irrespective of the usage to which it is subjected. The side portions of the vamp extend fully 25 along the sides of the heel, but are spaced slightly at the back of the heel, as indicated at 27, so as to dispense with the extra thickness resulting from the seam 28 connecting these side portions of the upper along the 30 back. The reinforcing strip 22, as shown in Fig. 8, overlaps the back portions of the vamp and its side edges are stitched thereto, as shown at 29. The front portion of the 35 upper is shown as well open and provided with pairs of straps 30 for the connection of a lacer 31. I provide, however, a peculiar form of tongue 32 stitched or otherwise secured at 33 at its lower end only to the instep portion of the vamp. The tongue 38 40 is formed of two parts stitched together at 34 along the longitudinal center, the two parts being cut from a stiff quality of waterproof cloth and so designed that when connected along the seam 34, the tongue as a 45 whole will conform directly and properly to the shape of the wearer's ankle. The tongue may be of any desired width so as to accommodate the lacing means to different sizes of ankles without discomfort.

50 At 35 I show a strip of ornamental material stitched across the instep from one side of the shank to the other. I also show a

heel piece 36 inserted over the clenched heel fasteners to protect the wearer's heel.

55

I claim:

1. In a bathing shoe, the combination of a waterproof out sole, a metal arch support, means to secure the arch support to the shank portion of the out sole, certain of said securing means being located in the 60 longitudinal center of the arch support, said arch support having a notch formed in the longitudinal center of the heel end, a heel, an insole, and fastening devices securing the heel to parts above it, one of said fastening devices passing through the notch at the rear end of the arch support in longitudinal alinement with said central arch support fastening means.

2. In a bathing shoe, the combination of 70 an out sole, an insole, both of waterproof material, a metal arch support between the two soles at the shank portion thereof, the heel end of the arch support being longitudinally notched; a leather pad between the 75 notched end of the arch support and the insole, a heel comprising a plurality of lifts and fastening devices passing through the heel, the sole members and the pad, one of said fastening devices passing through said 80 notch.

3. In a bathing shoe, the combination of a one piece vamp and upper, the lower free edges of which lie adjacent to but spaced from the vertical central line at the rear of 85 the heel, a reinforcing strip extending vertically over the space between said free edges, the edges of the strip being stitched to the edge portions of the vamp and upper, a quarter of two parts secured to the rear 90 portion of the vamp and upper, the two parts of the quarter being connected by a vertical seam back of the space aforesaid between the edges of the vamp and upper, a hard rubber counter between the back 95 portion of the quarter and the reinforcing strip, a heel, the lower end of the reinforcing strip being slotted longitudinally and lying over the heel, and fastening devices 100 passing upwardly through the heel, the bottom of the counter and the said lower end of the reinforcing strip.

JOEL KIMMEL.
